(57) **CLAIM**

The ornamental design for a display cabinet, as shown and described.

DESCRIPTION

FIG. 1 is a front elevational view of a display cabinet showing my new design.

FIG. 2 is a right-side elevational view thereof, with the left-side elevational view thereof being a mirror image;

FIG. 3 is a top plan view thereof;

FIG. 4 is a rear elevational view thereof; and,

FIG. 5 is a bottom plan view thereof.

The broken lines in FIG. 1 show environment and form no part of the claimed design.
